ANTISPLASH CONSTRUCTION FOR
FOOTWEAR

Curry Ora Walper, Kitchener, Ontario, Canada

Application July 10, 1945, Serial No. 604,198

4 Claims. (Cl. 36—70)

1

This invention relates to improvements in heels of footwear wherewith the water attracted to the heel and raised with the heel from wet surfaces is cast from the heel in a direction away from the opposite leg.

Reference is made to my previous Patents 2,331,062 of October 5, 1943 (Case 1); 2,349,216 of May 16, 1944 (Case 2); 2,380,349 of July 10, 1945 (Case 3); and 2,395,597 of February 26, 1946 (Case 4); and my application No. 539,521 (Case 5); now abandoned.

The exact cause, or the theory of the exact source of the deposit on the backs of legs has long been a controversial dispute. I claim having isolated both the cause and the source of it by persevering experiment and a series of exhaustive tests, as well as having originated the means of obviating the deposit. The cause and source have been fully set forth in the specifications of my previous inventions, and so need not be further discussed.

Each of my inventions performs well per se when worn by persons who walk normally, i. e., with the median line of their feet substantially parallel to the path, and by certain of those who walk in the manner known as toeing out. These two types of walkers will be referred to herein-after as "normals" and "toers-out," respectively.

As can be well understood, it is not an easy matter to detect by observation exactly what happens to the drip picked up by the feet, that is to say, where all of it goes. Similarly it is no easy matter to observe exactly where the deposit which accumulates on the back of legs originates. The researcher would have to be scientifically equipped, say with an elaborate arrangement of slow motion photography, and with perhaps a robot as a subject, in order to provide the point; and even then it might fail in expected revelations. Consequently, I have had to rely first on theory, next on experiment, and finally on result.

One thing that I have discovered is that there are an incalculable number of different types or species of walking in each of the main separable classes, i. e., the toers-out, the normals, and the toers-in. Again, it would take slow motion equipment to record even some of these class species, and then we could perhaps go on and on indefinitely, and finally it could be well nigh impossible to type all of them, or even to sub-group them.

Here it can be mentioned, however, that persons who toe-in do not require any of my equipment. Toers-in do not soil their legs from their own feet. The reason for this is that when the

foot is pitched heel up after breaking contact with the ground the edge of the heel where the breast and the bottom of the tread join is declined toward the outer side of the foot, and hence the drip runs down that edge by molecular adhesion and is discharged on the side of the heel opposite the side adjacent its mate. Such edge may well be termed a conductor, or conductor edge, and henceforth will be so called.

10 Normals are taken care of in my earlier inventions.

Contrary to toers-in, toers-out obviously decline the conductor edge inwardly, or toward the mate; and the degree of declination varies, not 15 only according to that of the toe-out, but also according to the degree of the twist during the heel up pitch of the feet, which is found to vary considerably in a group of persons, all having substantially the same degree of toe-out. While 20 all toers-out then have an inwardly directed declivity, some of the declivities are gentle while others vary up to the quite precipitous.

The toers-out whose manner of walking produces a gentle declivity to the aforesaid edge, 25 or one which would be considered more or less normal for a toer-out, have been provided for by my structures according to Cases 2, 3 and 4 in which the drip is cast from the inner or low forward corner of the heel parallel with the path or, in other words, not obliquely in the direction of the path of its mate as with conventional footwear. But in circumstances of toers-out, whose quite common characteristic of effecting a precipitous declivity precludes the successful operation 35 of my previous structures, in that the drip flows too fast and as a consequence gravity beats molecular adhesion so to speak, I have devised a structure for directing the drip to the opposite or outer side of the heel where it is cast on the outside instead of the inner side nearest its mate, exactly in the same manner as toers-in discharge their drip when equipped with conventional footwear and hence make no offensive deposit.

40 45 The object of the present invention is to provide in footwear worn by toers-out and wherein the conductor edge would normally decline toward the mate during the heel up pitch of the foot, a formation whereby that edge naturally declines in the opposite direction, or away from the mate.

With the above and other objects in view, as 50 55 will be hereinafter apparent, the invention consists in general of certain novel details of construction and combinations of parts hereinafter

fully described, illustrated in the accompanying drawings and specifically claimed.

In the accompanying drawings like characters of reference indicate like parts in the several views, and:

Figure 1 is a side elevation of a heel constructed in accordance with the present invention, the view being the inner side, or the right hand side of the heel for an article of footwear for wear on the left foot, and showing a certain extended portion.

Figure 2 is an opposite or outer side view of the structure of Figure 1.

Figure 3 is a front elevation of the same showing the heel breast.

Figure 4 is a sectional plan view taken on the line 4-4 of Figure 2.

Figure 5 is a partial rear and outer side perspective view as seen after the left foot has broken contact with the ground and pitched to the rear.

Figure 6 is a view similar to Figure 2 of a modified form of the invention.

Figure 7 is an elevation of the inner side of a heel showing a modified form of the invention.

Figure 8 is a bottom view of Figure 7.

In the drawing 10 indicates a heel and 11, the shank portion of an overshoе or the like.

The breast of the heel has a tongue-like portion 12 which extends in advance of the plane of the breast and spaced from or free of the shank portion 11. The bottom or tread surface of the extended portion is preferably on a plane common with that of the heel.

The tip 12a of the tongue-like portion 12 is offset from the median line of the article of footwear well to the outer side thereof, and the conductor edge 12b which is formed by the juncture of the breast and the heel bottom or tread sweeps from the forward inner corner 10a of the heel to the tip 12a.

The edge 12b forms a conductor for the drip from all parts or surfaces of the heel. The drip water drains from the upper reaches of the heel to its lower margins, then when the foot is pitched heel up after breaking with the ground to the position in Figure 5 the water runs down the bottom of the heel by molecular adhesion in defiance of gravity clean to the conductor edge 12b. It is to be understood that when the heel is lifted from the ground it is in an unloaded condition and whenever hereafter in the specification and claims the unloaded condition of the heel is referred to it is off the ground.

As it reaches that edge in the case of a normally formed heel it is conducted by it toward whichever forward corner of the heel is lowermost, similarly by molecular adhesion, and the water is cast from that particular corner.

From an observation of Figure 5 it will be evident that the water will drain toward the outer side and be cast from the tip 12a. Thus the drainage is conducted to the side of the footwear which is opposite to the side nearest its mate, this notwithstanding the fact that the heel is actually tilted toward its mate, or toward the inner side.

The angle of the edge formed by the juncture of the breast and the tread surface of a conventional heel, and which runs toward the inner corner of the heel when the foot is up pitched, is indicated by the dot-and-dash line 12c, also in Figure 5.

For some types of toers-out it is found expedient to provide a declivity to the bottom of the heel tread (this declivity being considered as

such when compared to the substantially parallel planes of the bottom of the heel tread and the heel saddle or seat of a conventionally formed overshoе) running from the rear of the heel to the tip of the extended portion whereby the drainage is directed along the tread bottom to the tip immediately the footwear breaks with the ground. Such a declivity is noticeable in all the elevational figures, but is particularly noticeable in Figure 1 wherein it is indicated by 10b, inasmuch as in this view its surface appears in perspective form.

As in Case 3 (where the tread declivity, however, is directed to the opposite side) in order that when the heel is put to the ground under the weight of the wearer the foot will not be thrown out of normal vertical posture, the thickness of the differential from normal or level is preferably built down by a wedge 13 of relatively elastic and compressible material or a layer 13a (Figure 6) of similar material, which reforms itself on the shifting of the load to the opposite foot.

In the modified form of my invention shown in Figures 7 and 8 a conductor edge 14 is provided by stepping up a diagonal portion 15 of the front of an otherwise conventionally shaped or proportioned heel tread. While this form of my present invention may be said to be more particularly for toers-out effecting a more or less gentle inwardly directed declivity, it has also been found in at least some instances to take care of those whose declivity is relatively precipitous, and more often when in addition the bottom of the heel is declined as sometimes with the use of the tongue-like deformation of the breast, and as it is also indicated at 16 in Figures 7 and 8.

There has thus been provided a simple and efficient device of the kind described and for the purpose specified.

It is obvious that minor changes may be made in the form and construction of the invention without departing from the material spirit thereof. It is not, however, desired to confine the invention to the exact form herein shown and described, but it is desired to include all such as properly come within the scope claimed.

I claim:

1. In a heel for footwear, a conductor for directionally influencing molecularly adhered drip drainage across the heel substantially from the inner to the outer side thereof, consisting of a deformation of the heel breast characterized by the lower portion thereof extending in advance of its normal plane as a tongue and free of the shank portion of the footwear, said extended portion running in an oblique sweep substantially from the inner to the outer side so that the tip of said extended portion lies in the region of the outer side of the footwear.

2. The device as defined in claim 1 wherein the plane of the heel tread and said extended portion inclines forwardly and downwardly from the rear towards the tip of the extended portion in an unloaded condition.

3. Footwear including a hollow heel and heel tread portion, said portion extending as a tongue in advance of the plane of the heel breast and free of the shank portion of the footwear, said extended portion running in an oblique sweep to its tip substantially from the inner corner of the heel whereby the tip of said extended portion lies in the region of the outer side of the footwear, said extended portion inclining forwardly and downwardly from the rear towards

the tip of said extended portion in an unloaded condition.

4. In a heel for footwear, a conductor for directionally influencing molecularly adhered drip drainage across the heel substantially from the inner to the outer side thereof, characterized by a sweeping deflection of at least a portion of the heel breast from a normal plane, said deflected portion extending substantially from the inner corner of the heel forwardly and toward the outer side of the footwear and free of the shank portion thereof said deflected portion extending for-

wardly and downwardly from the rear towards the tip of said extended portion in an unloaded condition.
